US0D1096588S

(12) **United States Design Patent** (10) **Patent No.:** **US D1,096,588 S**
(45) **Date of Patent:** **** Oct. 7, 2025**

(54) **CAR PHONE HOLDER**

(71) Applicant: **Shenzhen Joyroom Technology Co., Ltd**, Shenzhen (CN)

(72) Inventor: **Pingjun Sun**, Shenzhen (CN)

(73) Assignee: **Shenzhen Joyroom Technology Co., Ltd**, Shenzhen (CN)

(**) Term: **15 Years**

(21) Appl. No.: **29/936,230**

(22) Filed: **Apr. 8, 2024**

(30) **Foreign Application Priority Data**

Nov. 8, 2023 (CN) 202330729462.7
